Patented Sept. 23, 1975

236,877

ESCUTCHEON FOR A DEADLOCK

Raymond U. H. Tegner, Lodi, Wis., assignor to
Amerock Corporation, Rockford, Ill.

Filed Jan. 4, 1974, Ser. No. 430,938

Term of patent 14 years

Int. Cl. D8—09

U.S. Cl. D8—179

FIG. 1 is a front view of an escutcheon for a deadlock.
FIG. 2 is a side view of the escutcheon as seen from the right of FIG. 1.

FIG. 3 is a top view of the escutcheon.
FIG. 4 is a bottom view of the escutcheon.
FIG. 5 is a sectional view taken along the line 5—5 in FIG. 1.

I claim:

The ornamental design for an escutcheon for a deadlock, as shown.
